Primary Examiner — Amy C Wierenga*Assistant Examiner* — Jenny lou M Binas(74) Attorney, Agent, or Firm — Faegre Drinker Biddle & Reath LLP(57) CLAIM

We claim the ornamental design for a vacuum cleaner wand, as shown and described.

DESCRIPTION

FIG. 1 is a top perspective view of a vacuum cleaner wand showing our new design;

FIG. 2 is a top view thereof;

FIG. 3 is a bottom view thereof;

FIG. 4 is a left side view thereof;

FIG. 5 is a right side view thereof;

FIG. 6 is a rear view thereof; and,

FIG. 7 is a front view thereof.

The broken lines shown in the drawings illustrate portions of a vacuum cleaner wand that form no part of the claimed design.
